UNITED STATES PATENT OFFICE

2,268,652

MEANS FOR SEPARATING PARTICLES OF
SOLID MATERIAL BY FLOTATION

Russell Scott Ellis, Vineland, N. J.

Application April 19, 1939, Serial No. 268,667

9 Claims. (Cl. 209—211)

My present invention relates to methods and means of the same general character as disclosed in Letters Patent of the United States No. 2,104,537 granted to me January 4, 1938, and No. 2,146,672 granted to me February 7, 1939, and is applicable to any material particles of different sizes or specific gravity, or both, for instance, natural sands, comminuted stone, coal, vegetable grains, or any other substances, by the application thereto of water or other fluid or mixture of fluids under pressure to effect flotation thereof, and consequent separation of such particles.

The apparatus disclosed in said patents includes a plurality of separator casings, utilized as distinct receptacles for the material to be treated, disposed in a vertical series; and connected in series relation by conduits through which solid material which is not precipitated in the lowermost receptacle is delivered into the next higher receptacle, and the material which is not precipitated in the second receptacle is delivered into a third receptacle, and so on, the materials precipitated in the several receptacles being discharged separately from the bottoms thereof, and the finest materials, finally separated by flotation, being discharged from the top receptacle.

In the form of my invention chosen for illustration herein, as in each of said patents, the separator casing has a conical portion with its apex extending vertically downward, and has an inlet conduit for the material to be separated extending tangentially into one side thereof below the top, and an outlet conduit extending tangentially from the upper part of the casing, whereby the material stream flows circumferentially and centrifugal separation is effected. An axial inlet conduit for the flotation fluid extends vertically through said casing in coaxial relation therewith. That conduit is connected with two distinct flotation fluid supply conduits, respectively above and below said casing, through either or both of which flotation fluid may be delivered into the casing under pressure and including means for varying the effective area of the orifice through which the flotation fluid is discharged into the casing, whereby gravitational separation is effected. An outlet is provided extending laterally at the lower end of the casing through which the material precipitated in the casing is discharged.

It is highly important to the efficiency of such apparatus to provide means to variably limit, predetermine, and control the back pressure of

5 the flotation fluid in the apparatus; which tends to vary with momentary variations in the quantity of raw solid material supplied to the apparatus, viscosity of the fluid, power supply, etc. 10 My present invention provides improved means for controlling and regulating such back pressure and the centrifugal force available for separation, by varying the pressure under which the flotation fluids are supplied to the apparatus. 15 Such control is effective with respect to one or more columns of fluid, as to their relative pressures and rate of flow, and with reference to one or more adjustably variable outlets for fluid. 20 Such control is applied to a pump motor, or motors, which may be either electrically or mechanically energized, to produce the initial pressure upon said fluids.

25 My invention includes the various novel features of construction, arrangement, and method of operation hereinafter more definitely specified.

30 In said drawings; Fig. I is a diagrammatic elevation, partly in section, of apparatus exemplifying my invention, particularly designed to employ water as a flotation and cleansing fluid. 35 Fig. II is a diagrammatic elevation, partly in section, of the fluid impelling means indicated in the lower portion of Fig. I, but on a larger scale. Fig. III is a diagrammatic elevation, partly in section, of a portion of the apparatus at the upper end of Fig. I, but on a larger scale. Fig. IV is a larger longitudinal sectional view of one of the ball valve casings for controlling the flotation fluid, of which two are shown at the right of Fig. III. Fig. V is a diagrammatic elevation, 40 partly in section, similar to Fig. III, but showing apparatus particularly designed to employ atmospheric air or other gaseous fluid to effect flotation of the solid materials. Fig. VI is a longitudinal vertical sectional view taken on the line VI, VI in Fig. II in the direction of the arrows on said line; showing the oscillatory impeller operatively connected with a rheostat for controlling the electric motor for driving the fluid pump shown at the right hand side of Fig. I and indicated diagrammatically at the right hand side of Fig. VI. Fig. VII is a diagrammatic elevation, 45 partly in section, of a portion of the apparatus at the upper end of Fig. I, but on a larger scale. Fig. VIII is a diagrammatic elevation, partly in section, similar to Fig. VII but showing apparatus particularly designed to employ atmospheric air or other gaseous fluid to effect flotation of the solid materials.

50 Referring to Figs. I and II; the masonry base

1 supports the metallic tower comprising the four vertical I-beam columns 2 connected by horizontal girders 3 capped by the overhanging roof structure 4 which is also supported by the additional columns 2' shown in Fig. I. Said tower supports eight conical separator receptacles 5, 6, 7, 8, 9, 10, 11, and 12, which are similar in construction but disposed at successively higher levels in said tower in a helically ascending series.

The central column 15 is a cylindrical pipe through which a classifying fluid, for instance water, is supplied by the centrifugal pump 16. As indicated in Fig. I, said pump 16 is actuated by the electric motor 17 and receives the classifying fluid through the conduit 18 extending to any suitable source of supply, for instance, a subjacent body of water.

Said separator casings each have an axial inlet conduit for the flotation fluid extending vertically therethrough in coaxial relation therewith and respectively indicated at 5^a, 6^a, 7^a, etc. Each of said axial conduits is connected with two distinct flotation fluid supply conduits respectively above and below the casing and extending from said supply column conduit 15; the lower conduits being indicated respectively at 5^b, 6^b, 7^b, etc., and the upper supply conduits being indicated respectively at 5^c, 6^c, 7^c, etc.

Each of said separator casings has an outlet conduit extending tangentially from the upper part thereof and into the next higher casing, and indicated respectively at 5^d, 6^d, 7^d, etc. Said conduits 5^d, 6^d, 7^d, etc., conduct the lighter material which is not precipitated in the respective casings 5, 6, 7, etc. Each of said casings has an outlet conduit extending laterally at the lower end thereof through which the material precipitated in the casing is discharged; such conduits being indicated at 5^e, 6^e, 7^e, etc.

The material to be treated, for instance sand, is conveniently dredged from its natural bed and delivered mixed with water into the tank 20, indicated in Fig. I, through a rotary screen which eliminates particles larger than it is desired to treat. Said material to be treated is raised, mixed with water, through the conduit 21 by the centrifugal pump 22 from which it is discharged through the conduit 23 tangentially into the conical side of the lowermost separator 5, as indicated in Fig. I. Said pump 22 is conveniently actuated by the electric motor 25.

As shown in Fig. III; I find it convenient to variably predetermine the maximum pressure to which the fluid in the supply column 15 may be subjected, by such means as disclosed in my Patent 2,104,537, to wit, by maintaining the upper end of said conduit normally closed by the valve 27 which may be variably weighted in accordance with the number of cast iron pigs 28 placed therein. When that pressure is exceeded, said valve is lifted by the fluid in the column 15 which spills over into the hood 15' and escapes to waste through the conduit 29. However, in accordance with the present invention, that loss is minimized and normally prevented by other means connected to conduit 29, controlling the pressure to which the flotation fluid supplied to column 15 is initially subjected by the pump 22, as hereinafter described as connected to conduit 12^d for controlling the pump 16.

Such control of the initial pressure, and rate of flow of the stream of flotation fluid carrying the solid material in the several separator casings connected with pump 16, as above contem-

plated, is effected by the means shown in Figs. II, III, and VI, as follows:

As best shown in Fig. III, the outlet conduit 12^d for the uppermost separator casing 12, through which the lightest solid material not precipitated in said separator is discharged, directs such discharge into the float chamber 31 of the control casing 32, through passageways upon opposite sides of said chamber 31 formed by vertical partitions 31', each of which has several openings 31^a therethrough leading to said chamber. In order to variably predetermine the rate of discharge of flotation fluid from said float chamber and thus predetermine the effect of that fluid in said chamber upon the float 34; I find it convenient to provide the bottom of said chamber 31 with the seat 31^b for the disk 35 having the orifice 35'. I provide a series of such disks with orifices of different sizes which may be selectively utilized to thus determine the quantity of fluid dissipated from said float chamber which passes to waste through the outlet conduit 32' of said control casing 32.

Said float 34 is connected by the pivot 34' with the lever 36 which is fulcrumed on the pivot 36' in the bracket 32^a fixed on the left hand wall of the valve chamber 32^b in said control casing 32. Said lever 36 has rigidly connected therewith two arms 36^a and 36^b respectively extending upward and downward from said pivot 36' and respectively pivotally connected with valve plungers 38 and 39. The cylindrical valve plungers 38^a and 39^a are respectively axially adjustable upon said screws 38 and 39 which carry lock nuts 38^b and 39^b by which said plungers may be secured in adjusted position.

Said valve plungers 38^a and 39^a are respectively mounted for axial reciprocation in valve casings 40 and 41 respectively housing ball valves 40^a and 41^a. Said ball valves respectively control the openings of the ends of the two fluid conduits 42 and 43 leading from the fluid motor casing 45 shown in Figs. II and VI.

As shown in Fig. VII, the conduit 29 is provided with control mechanism similar to that shown in Fig. III as connected to the outlet conduit 12^d. The discharge from the conduit 29 is directed into the float chamber 131 of the control casing 132, through passageways upon opposite sides of said chamber 131 formed by vertical partitions 131', each of which has several openings 131^a therethrough leading to the chamber. In order to variably predetermine the rate of discharge of fluid from said float chamber and thus predetermine the effect of that fluid in said chamber upon the float 134; I find it convenient to provide the bottom of said chamber 131 with the seat 131^b for the disk 135 having the orifice 135'. I provide a series of such disks with orifices of different sizes which may be selectively utilized to thus determine the quantity of fluid dissipated from said float chamber through the conduit 132' of said control casing 132.

Said float 134 is connected by the pivot 134' with the lever 136 which is fulcrumed on the pivot 136' in the bracket 132^a fixed on the left hand wall of the valve chamber 132^b in said control casing 132. Said lever 136 has rigidly connected therewith two arms 136^a and 136^b respectively extending upwardly and downwardly from said pivot 136' and respectively pivotally connected with valve plunger screws 138 and 139. The cylindrical valve plungers 138^a and 139^a are respectively axially adjustable upon said screws

138 and 139 which carry lock nuts 138^b and 139^b by which said plungers may be secured in adjusted position.

Said plungers 138^a and 139^a are respectively mounted for axial reciprocation in valve casings 140 and 141 respectively housing ball valves 140^a and 141^a. Said ball valves respectively control the openings of the ends of the two fluid conduits 42 and 43 leading from the fluid motor casing 45.

As shown in Figs. II and VI, said motor casing 45 is a cylinder conveniently supported with its axis in horizontal position by rigid connection with the rectangular rheostat casing 46. As shown in Fig. II, said motor casing 45 has rigidly connected therewith the partition 45^a, supporting the vertically reciprocating bearing 45^b for the shaft 47 of the oscillatory fluid impeller piston blade 47^a. As shown in Figs. II and VI, said stationary partition 45^a carries three vertically extending springs 45^c which continually stress said bearing 45^b upwardly to seal its junction with shaft 47. The sealing shoe 47^b on the outer end of said impeller 47^a incloses the flat spring 47^c, which stresses it in contact with the inner cylindrical surface of said motor casing 45. The space in said casing 45 is thus divided into two opposite fluid chambers 48 and 49, respectively supplied with fluid through the ports 48^a and 49^a leading from the fluid supply conduit 50.

As shown in Fig. II, said conduit 50 is continually supplied with fluid under pressure, conveniently clear water, by means of the pump 51 actuated by the electric motor 52 to draw the supply of fluid through the conduit 50^a leading to any suitable source of water. Said water supply conduit 50 leading to the motor casing 45 has the by-pass conduit 50^b provided with the pressure gauge 50^c showing the fluid pressure in said conduit 50. Said by-pass conduit 50^b opens into the valve casing 50^d and is normally closed by the ball valve 54 under pressure of the spring 54^a, which pressure may be varied by the adjusting screw 54^b to variably determine the pressure at which the fluid may escape from said conduit 50 back into the conduit 50^a to the suction side of the pump 51.

The construction and arrangement above described are such that with the float 34 supported in the position shown in Fig. III, by the water in the float chamber 31; each of the ball valves 40^a and 41^a is slightly open to the same extent. In that position the water pressure in the two chambers 48 and 49 of the motor casing 45 is equal and the impeller blade 47^a occupies a vertical position between said chambers. However, if said float 34 is uplifted from the position shown in Fig. III by accumulation of water in said float chamber 31, the ball valve 40^a is moved to close the end of said conduit 42 and the ball valve 41^a is correspondingly opened to increase the effective open area of the end of said conduit 43. Consequently, the impeller blade which is balanced in vertical position by equal pressures in the chambers 48 and 49, is displaced counter-clockwise, as indicated in Fig. II, by increment of pressure in the chamber 49 and decrement of pressure in chamber 48 with which said conduits 42 and 43 are respectively connected. On the contrary, if said float 34 is lowered by subsidence of water in the float chamber 31 shown in Fig. III; said impeller 47^a is turned clockwise by increment of pressure in the chamber 48 and decrement of pressure in the chamber 49.

I utilize such oscillatory movement of the impeller element 47^a to control and vary the fluid pressure in the solid material supply conduit 23 and separator casings 5, 6, 7, etc., by the pump 22, by varying the amount of resistance in the energizing circuit of the pump motor 25. Similar float, valve, and motor control devices are connected with the conduit 29, to control the motor 17 and pump 16.

10 To thus control the motor circuits and consequent speed of operation of the pumps and consequent pressure, acceleration and deceleration of flow, of fluids in the system; I connect the shaft 47 of the oscillatory impeller 47^a with a rheostat drum 56 indicated by the dotted circle in Fig. II and shown, principally in elevation, in Fig. VI. As shown in Fig. VI, the drum 56 is arranged to control the motor 17 which, as indicated in Fig. I, is operatively connected with the pump 16 supplying flotation fluid to the column conduit 15. Said drum 56 has the arcuate contact plate 56^a secured thereon in cooperative relation with the spring switch contact 57, the upper end of which is rigidly connected with the stationary switchbar 46^a in said rheostat casing 46 and connected by the electrical conductor 17^a with the commutator 17^b by the brush 17^c. The brush 17^d is connected with the electrical conductor 17^e leading to the resistance grid 58 which has a series of branch conductors 59 leading from different portions thereof to respective similar spring switch contacts 60 rigidly connected at their upper ends with said switch bar 46^a and overhanging said drum 56, as shown in Figs. II and VI. Said drum 56 has a series of arcuate switch contact plates 56^b of different lengths rigidly secured thereon. Said arcuate switch contact plates 56^b are all connected in multiple with said contact plate 56^a, with the effect that as said rheostat drum 56 is turned in the direction of the arrow marked thereon in Fig. VI by counter-clockwise movement of the impeller 47^a, as shown in Fig. II; the resistance in the circuit of the motor 17 is increased by inclusion of more of the resistance grid 58 than in the position shown in Fig. VI; with the effect of decreasing the speed of rotation of said motor 17 and consequent decrease of speed in the rotation of the pump 16 and consequent reduction in the initial pressure of the fluid supplied through the column 15. On the contrary, when the impeller 47^a is turned clockwise in Fig. II, the resistance in the circuit of said motor 17 is decreased by inclusion of less of the sections of the grid 58, with consequent increment in the speed of rotation of said motor 17 and pump 16 and increment in the initial pressure of the flotation fluid supplied through said conduit 15 and the series of separator casings 5, 6, 7, etc. As above indicated, the purpose and effect of such automatic control of the pressure of the flotation fluid in the apparatus described is to compensate for the frequently recurring irregularities in the back pressure of the fluid in said apparatus, however occasioned, and by accelerating or decelerating the flow of the stream of fluid supplying the material to be separated, or the stream of clear flotation fluid, or both, independently, simultaneously or at different instants, but with continuing cooperation in attaining the desired control and regulation of the separating effect desired.

However, in some locations it is more convenient to drive the pumps 16 and 25 by connections with oil engines than by connection with

electric motors. Therefore, as shown in Fig. VI, I provide the right hand end of said rheostat drum 56 with the axial shaft 47^a, thus operatively connected with the shaft 47 of said impeller, to drive the gear 47^b which may be operatively connected with a valve controlling the operation of such an engine to thus mechanically control such an engine or engines by the operation of a fluid motor such as shown in the motor casing 45, instead of thereby effecting electrical control of an electric motor or motors.

Although I prefer to use water as the flotation fluid for natural sands, comminuted stone, and coal, as above noted, I may use atmospheric air or other gaseous fluids to effect flotation of other solid materials and I have shown in Fig. V apparatus similar to that shown in Fig. III, except that it is adapted for use of such lighter flotation fluids.

In Fig. V, the control casing 62 is similar to the control casing 32 except that it is normally maintained closed to prevent escape of the lighter fluids under pressure, by means of hinged lids 62^a and 62^b respectively covering the float chamber 64 and the valve chamber 65, both of which may be conveniently clamped in air tight relation with the casing 62 by the nut 62^c on the bolt 62^d. The float 66 is a disk pivoted at 66' on the lever 67 which is like the lever 36 and similarly arranged to operate ball valves 40^a and 41^a to control the outlet for the conduits 42 and 43 as above described. Said float 66 is normally upheld in the position shown in Fig. V in the cylinder 64' of the float chamber 64 by the compressed air or other gaseous fluid in the chamber 68 with which the outlet conduit 12^d of the separator 12 is connected as shown in Fig. V. The bottom of the chamber 68 is provided with any selected one of a series of perforated disks 69, similar to the disk 35 aforesaid, to determine the volume of flotation fluid which is dissipated from said chamber 68 and discharged from the control casing 62 by way of the conduit 70 which may lead to the atmosphere or to a dust collector. As said disks 69 are not accessible from the top of the control casing 62 as are the disks 35 used with the control casing 32 in Fig. III; I find it convenient to provide the bottom of the control casing 62 with a removable service door 62^e which is normally secured in fluid tight relation with said casing 62 by nuts 62^f.

As shown in Fig. VIII, when atmospheric air or other gaseous fluids are used to effect flotation of other solid materials, the conduit 29 is provided with control mechanism similar to that shown in Fig. V as connected to the outlet conduit 12^d. The discharge from the conduit 29 is directed into the control casing 162, similar to the control casing 132, except that it is normally maintained closed to prevent escape of the lighter fluids under pressure, by means of hinged lids 162^a and 162^b respectively covering the float chamber 164 and the valve chamber 165, both of which may be conveniently clamped in airtight relation with the casing 162 by the nut 162^c on the bolt 162^d. The float 166 is a disk pivoted at 166' on the lever 167, which is like the lever 136 and similarly arranged to operate ball valves 140^a and 141^a to control the outlet for the conduits 42 and 43 as described. Said float 166 is normally upheld in the position shown in Fig. VIII in the cylinder 164' of the float chamber 164 by the compressed air or other gaseous fluid in the chamber 168 with which the outlet con-

duit 29 of the hood 15' is connected, as shown in Fig. VIII. The bottom of the chamber 168 is provided with any selected one of a series of perforated disks 169, similar to the disk 135 aforesaid, to determine the volume of fluid which is dissipated from said chamber 168 and discharged from the control casing 162 by way of the conduit 170 which may lead to the atmosphere or to a dust collector. As said disks 169 are not accessible from the top of the control casing 162, as are the disks 35 used with the control casing 32 in Fig. III, I find it convenient to provide the bottom of the control casing 162 with a removable service door 162^e which is normally secured in fluid-tight relation with said casing 162 by nuts 162^f.

However, an essential feature of my invention is that tendencies to irregular operation of the apparatus and fluctuating back pressure of the fluids therein from instant to instant are controlled and the operation rendered substantially uniform despite such variations in the nature or rate of supply of the solid material, by controlling means dependent for its operation upon the fluctuating quantity of flotation fluid discharged from the apparatus whether the apparatus comprises one or more such casings; such control being effected by varying the initial pressure under which flotation fluid is supplied to the apparatus, and thereby accelerating or decelerating the flow thereof in the apparatus, and specifically by controlling the rate of operation of a pump or pumps. An adjunctive feature is that the fluid discharge outlet, used for such control, is provided with means for rendering its effective area adjustably variable; the latter means being exemplified by the perforated plates 35 and 69, shown respectively in Figs. III and V.

Therefore, I do not desire to limit myself to the precise details of construction, arrangement, or method of operation herein set forth, as it is obvious that various modifications may be made therein without departing from the essential features of my invention as defined in the appended claims.

I claim:

1. In means for separating particles of solid material by flotation, the combination with a series of vertical conical separator casings disposed at different levels, in an ascending series, each having a tangential inlet at the lower portion thereof and a tangential discharge outlet at the upper portion thereof, the discharge outlet of the lowest casing being connected with the inlet of the next higher casing, and so on in the series; of means for supplying the material to be separated, in flotation fluid, to the lowest casing in the series, and thence to the other casings in the series through the respective outlets and inlets thereof, including a first pump; a vertical conduit column, exterior to said casings, but having branches respectively extending axially through said casings and connected with said column at both the lower and upper ends of said branches; means for maintaining said column charged with flotation fluid, free from solid material, including a second pump in communication with the lower end of said column; and means for automatically variably controlling the centrifugal force of the fluid tangentially injected into said casings from said first pump, and the levitating effect of the fluid delivered into said casings from said second pump, by variations in the speed of operation of each of said

pumps, respectively in accordance with variations in the viscosity of the fluid discharged through two variably restricted outlets, respectively from the uppermost casing, and from the top of said column, and thereby increasing the speed of operation of said pumps and consequent kinetic pressure upon said fluid in accordance with increase in viscosity of the fluid, and vice versa, including two pump control casings one in communication with the tangential discharge outlet from the uppermost conical separating casing, arranged to receive fluid from said outlet, and the other in communication with the top of said column, a restricted orifice at the bottom of each of said control casings, respectively determining the rate of the flow of fluid from said casings, in accordance with the variable viscosity of the fluid from the tangential discharge and in accordance with the variable volume of fluid discharged from the top of the column; two elements respectively subjected to the action of the fluid in said control casings and movable up and down therein in accordance with the respective temporary level of the fluid in said casings; valve means respectively in controlling relation with the speed of operation of said first and second pumps and respectively operatively connected with said movable elements and arranged to be opened and closed in accordance with the vertical movements of said elements by the fluid in the respective control casings; whereby the rate of operation of each of said pumps is automatically varied in accordance with the variation in viscosity of the fluid from the tangential discharge and in accordance with the variable volume of fluid discharged from the top of the column during its operation.

2. In means for separating particles of solid material by flotation, the combination with a series of circular separator casings disposed with their axes vertical, at different levels in an ascending series, each having a tangential inlet at the lower portion thereof and a tangential discharge outlet at the upper portion thereof, the discharge outlet of the lowest casing being connected with the inlet of the next higher casing, and so on in the series; means for supplying the material to be separated, in flotation fluid, to the lowest casing in the series, and thence to the other casings in the series through the respective outlets and inlets thereof, including a first pump; a vertical conduit column, exterior to said casings, but having branches respectively extending axially through said casings and connected with the column at both the lower and upper ends of said branches; means for maintaining the column charged with flotation fluid, including a second pump; and means for automatically controlling the centrifugal force of the fluid tangentially injected into said casings from said first pump, and the levitating effect of the fluid delivered into said casings from said second pump, by variations in the speed of operation of each of said pumps, respectively in accordance with variations in the viscosity of the fluid discharged through two restricted outlets, respectively from the uppermost casing, and from the top of said column, and thereby increasing the speed of operation of said pumps and consequent kinetic pressure upon said fluid in accordance with increase in viscosity of the fluid, and vice versa, including two pump control casings one in communication with the tangential discharge outlet from the uppermost conical separating casing.

arranged to receive fluid from said outlet, and the other in communication with the top of said column, a restricted orifice at the bottom of each of said control casings, respectively determining the rate of the flow of fluid from said casings, in accordance with the variable viscosity of the fluid from the tangential discharge and in accordance with the variable volume of fluid discharged from the top of the column; two elements respectively subjected to the action of the fluid in said control casings and movable up and down therein in accordance with the respective temporary level of the fluid in said casings; valve means respectively in controlling relation with the speed of operation of said first and second pumps and respectively operatively connected with said movable elements and arranged to be opened and closed in accordance with the vertical movements of said elements by the fluid in the respective control casings; whereby the rate of operation of each of said pumps is automatically varied in accordance with the variation in viscosity of the fluid from the tangential discharge and in accordance with the variable volume of fluid discharged from the top of the column during its operation.

3. In means for separating particles of solid material by flotation, the combination with a series of circular separator casings disposed with their axis vertical, at different levels in an ascending series, each having a tangential inlet at the lower portion thereof and a tangential discharge outlet at the upper portion thereof, the discharge outlet of the lowest casing being connected with the inlet of the next higher casing, and so on in the series; means for supplying the material to be separated, in flotation fluid, through the tangential inlet in the lowest casing in the series, and thence to the other casings in the series through the respective outlets and inlets thereof; a vertical conduit column, exterior to said casings, but having branches respectively extending axially through said casings and connected with said column at both the lower and upper ends of said branches; means for maintaining said column charged with flotation fluid, connected with the lower end of said column; and respective means for automatically varying the centrifugal force of the fluid injected tangentially into said casings, and the levitating effect of the fluid delivered into said casings from said column, respectively in accordance with variations in the viscosity of the fluid discharged, including two pump control casings one in communication with the tangential discharge outlet from the uppermost conical separating casing, arranged to receive fluid from said outlet, and the other in communication with the top of said column, a restricted orifice at the bottom of each of said control casings, respectively determining the rate of the flow of fluid from said casings, in accordance with the variable viscosity of the fluid from the tangential discharge and in accordance with the variable volume of fluid discharged from the top of the column; two elements respectively subjected to the action of the fluid in said control casings and movable up and down therein in accordance with the respective temporary level of the fluid in said casings; valve means respectively in controlling relation with said means for supplying the materials to be separated and said means for maintaining said column charged with flotation fluid and respectively operatively connected with said mov-

able elements and arranged to be opened and closed in accordance with the vertical movements of said elements by the fluid in the respective control casings; whereby the rate of supply of the material to be separated in said casings and the rate of charging said column with flotation fluid is automatically varied in accordance with the variation in viscosity of the fluid from the tangential discharge and in accordance with the variable volume of fluid discharged from the top of the column during the supplying and charging operations.

4. In means for separating particles of solid material by flotation, the combination with a vertical conical separator casing disposed with its apex downward, having a tangential inlet at the lower portion thereof, and a tangential discharge outlet at the upper portion thereof; means for supplying the material to be separated, in flotation fluid, through the tangential inlet in the 15 casing, including a first pump; a conduit column, exterior to the casing, but having a branch extending axially through the casing and connected with the column at both the lower and upper ends of the branch; means for maintaining the 20 column charged with flotation fluid, free from solid material, including a second pump; and respective means for simultaneously automatically controlling the centrifugal force of the fluid injected into the casing from the first pump, and the levitating effect of the fluid delivered into the casing from the second pump, by variations in the speed of operation of each of said pumps, in accordance with variations in the viscosity of the 25 fluid discharged, including two pump control casings one in communication with the tangential discharge outlet from the uppermost conical separating casing, arranged to receive fluid from said outlet, and the other in communication with the top of said column, a discharge orifice at the bottom of each of said control casings, respectively determining the rate of the flow of fluid from said casings, in accordance with the variable viscosity of the fluid from the tangential discharge and in accordance with the variable volume of fluid discharged from the top of the column; two elements respectively subjected to the action of the fluid in said control casings and movable up and down therein in accordance with the respective temporary level of the fluid in said casings; valve means respectively in controlling relation with said means for supplying the material to be separated and said means for maintaining said column charged with flotation fluid and respectively operatively connected with said movable elements and arranged to be opened and closed in accordance with the vertical movements of said elements by the fluid in the respective control casings; whereby the rate of supply of the material to be separated in said casings and the rate of charging said column with flotation fluid is automatically varied in accordance with the variation in viscosity of the fluid from the tangential discharge and in accordance with the variable volume of fluid discharged from the top of the column during the supplying and charging operations.

5. In means for separating particles of solid material by flotation, the combination with a circular separator casing disposed with its axis vertical, having a tangential inlet at the lower portion thereof, and a tangential discharge outlet at the upper portion thereof; a first pump means for supplying the material to be separated, 70

in flotation fluid, through the tangential inlet in the casing; a vertical conduit column, exterior to the casing, but having a branch extending axially through the casing and connected with the column at both the lower and upper ends of the branch; a second pump means for maintaining the column charged with flotation fluid; and respective means for automatically controlling the centrifugal force of the fluid injected tangentially into the casing, and the levitating effect of the fluid delivered into the casing from the column, by variations in the rate of supply of fluid from each of said pump means, in accordance with variations in the viscosity of the fluid discharged from the outlet of the casing, and from the top of the column, and thereby increasing the rate of supply and consequent pressure upon the fluid in accordance with increase in viscosity of the fluid, and vice versa, including two pressure control casings one in communication with said tangential discharge outlet, and the other in communication with the top of said column, a restricted orifice at the bottom of each of said control casings respectively determining the rate of the flow of the fluid from said casings, in accordance with the variable viscosity of the fluid from the tangential discharge and in accordance with the variable volume of fluid discharged from the top of the column; two yieldable elements respectively subjected to the action of the fluid in said control casings and movable up and down therein in accordance with the respective temporary level of the fluid in said casings; valve means respectively in controlling relation with each of said pump means and respectively operatively connected with said movable elements and arranged to be opened and closed in accordance with the vertical movements of said elements by the fluid in the respective control casings; whereby the rate of operation of each of said pump means is automatically varied in accordance with the variation in viscosity of the fluid from the tangential discharge and in accordance with the variable volume of fluid discharged from the top of the column during its operation.

6. A structure as in claim 5; wherein the means for varying the pressure upon the fluid includes a lever supporting the yieldable element arranged to be levitated by back pressure of the fluid adjacent to the variable restricted outlet, from the top of the casing, in accordance with variations in the viscosity of the fluid; said yieldable element being raised as the viscosity increases, and vice versa.

7. A structure as in claim 5; wherein the means for varying the pressure upon the fluid includes a lever supporting the yieldable element arranged to be levitated by back pressure of the fluid adjacent to the variable restricted outlet from the top of the column, in accordance with variations in the viscosity of said fluid, said yieldable element being raised as the viscosity increases, and vice versa.

8. Apparatus as in claim 4; including a motor casing enclosing two fluid chambers, an oscillatory motor impeller continually separating said chambers and subjected to the opposed pressures of fluid in said chambers; two fluid conduits leading respectively from said chambers to the respective automatically operative valves; whereby, said valves control the admission of fluid to said chambers and vary the position of said im-

peller in accordance with the variations in viscosity of the fluid in the control casing.

9. Apparatus as in claim 5; including two motor casings, each enclosing two fluid chambers and an oscillatory motor impeller continually separating said chambers and subjected to the opposed pressures of fluid in said chambers, and having two fluid conduits leading respectively from said chambers to the two automatically

operative valves at one of the two pressure control casings; whereby, the two yieldable elements in the respective pressure control casings, respectively vary the position of the two impellers in the respective motor casings, in accordance with the variations in viscosity of the fluids in the respective pressure control casings.

RUSSELL SCOTT ELLIS.
